CLAIM

The ornamental design for display screen or portions thereof with set of icons as shown and described.

DESCRIPTION

The sole FIGURE shows a display screen or portions thereof with set of icons showing our new design.

The peripheral dashed broken lines illustrate a display screen or portions thereof and form no part of the claimed design. The thick broken lines contained by the peripheral broken lines illustrate icons and form part of the claimed design.

In the sole FIGURE, the solid line bracket indicates a set. The elements of the set are arranged relatively on the drawing sheet for the convenience of illustration and the placement of each element relative to another, or to the drawing sheet, forms no part of the claimed design.
